FUEL BURNER

Richard H. Tilghman, East Orange, N. J., assignor to The Babcock & Wilcox Company, Newark, N. J., a corporation of New Jersey

Application April 28, 1936, Serial No. 76,837

5 Claims. (Cl. 122—235)

The present invention relates in general to fuel burners and more particularly to pulverized fuel burners adapted to discharge through a furnace wall incorporating a row of spaced fluid heating and wall cooling tubes.

The general object of my invention is the provision of an improved construction of fuel burning means of the type adapted to produce a plurality of separate streams of fuel and air for combustion in intimately mixed relation through the intertube spaces of a furnace wall incorporating a row of spaced tubes. A further and more specific object is the provision of a pulverized fuel burner of the character described constructed to provide a uniform distribution of pulverized fuel to a series of burner nozzles and ample flow area for combustion air around and between the burner nozzles, minimize deposition and coking of the fuel on and between the wall tubes and in the burner nozzles, facilitate access to the burner parts for inspection, cleaning and repair, and with a relatively low cost of manufacture, installation, and maintenance.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a sectional elevation of a pulverized fuel burning installation constructed in accordance with my invention;

Fig. 2 is a view mainly in section along the center line of the fuel burner shown in Fig. 1;

Fig. 3 is a view of one of the burner ports from the inside of the furnace;

Fig. 4 is a plan view of the burner tip shown in Figs. 1 and 2;

Fig. 5 is a section taken on the line 5—5 of Fig. 2; and

Fig. 6 is a side view of one of the burner fuel nozzles.

A fuel burner constructed in accordance with my invention is illustrated as installed in a horizontally inclined arch of a high fuel burning capacity furnace in which the arch is normally exposed in operation to high furnace temperatures. The arch is cooled at its inner side by a row of vertically extending transversely spaced fluid heating tubes 10 adapted to form a part

of a fluid circulating system, such as that of a steam boiler receiving heating gases from the furnace. The spaces between the tubes are closed by blocks or a layer of suitable heat resistant material 11, except over a rectangular area defining a burner port across which the tubes 10 extend in uniformly spaced relation. The fuel burning means are preferably mounted on the arch so as to discharge fuel and air downwardly through the intertube spaces of the burner 10 port into the furnace. 5

My improved burning means comprise a casing 12 having an inlet 12a connected to a suitable source of secondary air for combustion, normally at a relatively high temperature. Along 15 the upper and lower ends of the burner port are arranged inclined curved baffles 13 and 14 respectively, arranged in downwardly converging relation. The spaces between the baffles 13 and 14 and the corresponding walls of the casing 12 are filled with initially plastic refractory material 15 with inner surfaces shaped to cooperate with the baffles 13 and 14 in providing a streamlined converging flow path for the secondary air to the burner port around the corresponding ends 20 of the burner nozzles, hereinafter described, tending to restrict the lateral expansion of the fuel streams in the furnace and aid in preventing fuel particles from eddying back into the air casing. An inclined baffle 16 along one of the 25 remaining walls of the casing contributes to this effect. The casing 12 is illustrated as being laterally subdivided by one or more vertical partition walls 17 to form separate secondary air supply compartments for a plurality of fuel burners arranged side-by-side transversely of the furnace arch. 30

My improved fuel burner is especially adapted for the burning of pulverized coal. The fuel supply means include an elbow conduit 20 externally of the casing 12 and having a removable flat deflection plate 21 arranged in the outer wall of the elbow. The down-stream section of the elbow is flared transversely of the arch and has a flanged connection with a distributing conduit 22 extending into the casing 12. The conduit 22 is of transversely elongated rectangular cross-section and has one pair of opposite sides shaped to provide a progressively flaring continuation of the elbow 20 towards the discharge end of the conduit 22, with its remaining pair of opposite sides slightly converging in a normal direction. An external flange 23 is welded to the lower end of the conduit 22 and detachably 35 40 45 50 55

connected to a similar flange 24 welded on the upper end of a burner tip member 25.

The burner tip member 25 is of welded construction and divided into a series of discharge nozzles 26, 27, and 28 spaced transversely of the fuel burner port and having their discharge ends terminating in a plane parallel to and at the upper or outer side of the axial plane of the arch tubes 10. Each of the fuel nozzles is formed by 10 a pair of curved side plates 30 welded along their meeting edges to form a flow passage of transversely elongated rectangular cross-section. The end plates 30 progressively diverge in a direction normal to the direction of flare of the conduit 22. The side plates 30 progressively converge towards a throat 31 adjacent the discharge end of the nozzle, and then diverge at an angle of approximately 15° relative to one another for the remaining portion of their length. Each of the nozzle passages is relatively shaped and proportioned as to flow area to obtain the desirable Venturi effect and discharge a fuel stream having substantially parallel straight sides. The 25 nozzle passages are made relatively wide even at the throat 31 to reduce their tendency to plug with fuel and render them easier to clean in the event they should plug. The number of nozzles per distributing conduit is relatively small to 30 facilitate uniform distribution of the fuel thereto and reduce the cost of construction. Only three nozzles are included in each burner tip in the embodiment illustrated, i. e., the oppositely arranged end nozzles 26 and 28, and the middle 35 or intermediate nozzle 27. The adjacent side plates 30 of adjacent nozzles are welded together at their upper ends, and the welds protected by wear bars 32.

With a distributing conduit 22 of the shape illustrated and the elbow 20 receiving a supply of pulverized coal and primary air, it has been found in practice that the heavier coal particles tend to flow along the narrow side walls of the conduit. To provide greater uniformity in the 45 amounts of fuel discharged by the several nozzles, the nozzles are constructed and relatively proportioned to provide a cross-sectional flow area at the entrance end of the intermediate nozzle 27 greater than the flow area at the entrance end 50 of the end nozzles 26 and 28.

In accordance with my invention, the adjacent fuel nozzles are spaced substantially twice the spacing of the tubes extending across the burner port, and the nozzles arranged to discharge 55 against the outer side of corresponding tubes 10. The tubes in the path of discharge of the fuel streams are provided with curved protector plates 35 shaped to fit and welded to the outer side thereof along substantially the full length of 60 the tube portions extending across the burner port. With this arrangement the pulverized fuel and primary air stream discharged from each nozzle will impinge upon the upper side of the corresponding protector plate 35 and be dispersed 65 thereby so as to discharge through the intertube spaces at opposite sides of the tube impinged. The protector plates 35 and wall tubes upon 70 which they are mounted thus collectively act as fuel dispersal devices subdividing the individual fuel streams.

The spaces 36 between the nozzles open at their ends to the air casing 12 and serve as flow 75 passages for secondary air between the fuel streams from the fuel nozzles. The secondary air streams from the inter-nozzle spaces 36 are

subdivided by the intermediate tubes 10 between the intertube spaces at opposite sides thereof, so as to provide converging streams of fuel and secondary air flowing through each intertube space across the burner port. The presence of the tubes 10 in the path of the secondary air streams causes the subdivided fuel streams from each nozzle to be intimately mixed with secondary air before coming into contact with the fuel streams discharged from the adjacent nozzles, and the secondary air streams deflected by the tubes 10 tend to straighten the subdivided fuel streams entering the furnace.

While the intermediate nozzle 27 has its discharge end above and parallel to the corresponding tube 10 and its axis of discharge normal to and intersecting the longitudinal axis of the corresponding tube, the end nozzles 26 and 28 are advantageously arranged with their axes of discharge slightly offset toward the intermediate 15 nozzle from the longitudinal axes of the corresponding tubes, as indicated in Fig. 2. This relative offset arrangement provides a substantially equal distribution of each fuel stream from the 20 end nozzles between the two intertube spaces at 25 opposite sides of the corresponding tube 10, as the fuel streams are found to be heavier towards the outer end walls of the end nozzles and unless such an offset arrangement is provided, a larger amount of fuel would pass through the end intertube 30 spaces. The fuel streams passing through the end intertube spaces are impinged upon by the air streams passing around the corresponding 35 ends of the burner tip. The arrangement of the fuel nozzles above alternate burner port tubes only also provides a more open construction of the fuel burner, rendering it easier to inspect 40 and remove any coke forming in the intertube spaces due to the deposition and burning of coal particles therein.

The fuel discharge parts are supported in position by brackets 37 mounted on the arch tubes at opposite ends of and connected to bars 38 on the intermediate fuel nozzle 27.

The outer surfaces of the burner tip are normally exposed to higher temperatures than the inner surfaces due to a secondary air temperature normally higher than the primary air temperature, and the arrangement of the burner tip in a position in which it will absorb some radiant 45 heat from the furnace. This is particularly disadvantageous in furnaces having more than one burner and in which not all of the burners are in operation at the same time. The introduction of the pulverized coal into fuel nozzles having a 50 high metal temperature would cause some of the coal particles to deposit therein and coke. To reduce the temperature of the nozzle parts, the outer surfaces thereof are advantageously provided with a layer 40 of initially plastic insulating material adapted to be held in position 55 on the nozzle by a multiplicity of metallic projections integrally connected to the nozzle surfaces. Such projections are preferably in the form of heavy nails 41 having their shank portions 60 welded to the surface of the nozzles and their head portions at the outer end thereof. The nails 41 are interwoven with wire 42, as 65 indicated in Fig. 6. The refractory material 40 is applied to the nozzle surfaces after the nails 70 are in position, and serves as an embedding material for the same.

When one of the fuel burners has been out of service for a period while the furnace is in use, the fuel discharge parts tend to acquire a rela- 75

tively high temperature due to the radiant heat absorbed. To reduce the temperature of the burner parts, a nozzle 45 is advantageously employed in the elbow conduit 28 and directed to discharge a controllable supply of a cooling gas, such as compressed air, through the fuel burner passages before any pulverized coal and primary air are introduced.

While in accordance with the provisions of the statutes I have illustrated and described herein the best forms of my invention now known to me, those skilled in the art will understand that changes may be made in the form of the apparatus disclosed without departing from the spirit 15 of the invention covered by my claims, and that certain features of my invention may sometimes be used to advantage without a corresponding use of other features.

I claim:

1. In combination with a furnace wall having a fuel burner port formed therein and a plurality of wall tubes uniformly spaced transversely of said port, fuel burning means arranged to discharge through the spaces between the wall tubes extending across said port and comprising a fuel conduit terminating in a plurality of transversely spaced fuel nozzles terminating at the outer side of the plane of said wall tubes, said nozzles being arranged so as to have the fuel streams discharged therefrom impinge on corresponding wall tubes and be divided thereby between the adjacent intertube spaces, adjacent nozzles being transversely spaced at least substantially twice the spacing of adjacent wall tubes, 30 and an air supply casing surrounding said nozzles and communicating with the spaces between adjacent nozzles and said intertube spaces so as to provide streams of air through the intertube spaces adjacent the tubes between the tubes impinged upon by the fuel streams discharged from 35 said nozzles.

2. In combination with a furnace wall having a fuel burner port formed therein and a plurality of wall tubes spaced transversely of said port, pulverized fuel burning means arranged to discharge through the spaces between the wall tubes extending across said port and comprising a pulverized fuel conduit terminating in a plurality of transversely spaced fuel nozzles terminating at the outer side of the plane of said wall tubes, 45 said nozzles having their discharge ends arranged so as to have the fuel streams discharged therefrom impinge on corresponding wall tubes and be divided thereby between the adjacent intertube spaces, said nozzles being transversely spaced sufficiently to impinge only on alternate wall tubes, and an air supply casing communicating with the spaces between adjacent nozzles and said intertube spaces so as to provide streams of air through the intertube spaces at opposite sides of the tubes between the tubes impinged upon by the fuel streams discharged from said nozzles.

3. In combination with a furnace wall having a fuel burner port formed therein and a plurality

of wall tubes spaced transversely of said port, pulverized fuel burning means arranged to discharge through the spaces between the wall tubes extending across said port and comprising a series of transversely spaced fuel nozzles terminating at the outer side of the plane of said wall tubes, said nozzles having their discharge ends arranged so as to have the fuel streams discharged therefrom impinge on corresponding wall tubes and be divided thereby between the adjacent intertube spaces, the end nozzles having their discharge ends laterally offset from the corresponding tubes toward an intermediate nozzle, and an air supply casing communicating with the spaces between adjacent nozzles and said intertube spaces.

4. In combination with a furnace wall having a fuel burner port formed therein and a plurality of wall tubes uniformly spaced transversely of said port, pulverized fuel burning means arranged to discharge through the spaces between the wall tubes extending across said port and comprising a pulverized fuel conduit terminating in a series of transversely spaced fuel nozzles terminating at the outer side of the plane of said wall tubes, said nozzles having elongated discharge ends arranged with their longitudinal axes parallel to the axes of and so as to have the fuel streams discharged therefrom impinge on corresponding wall tubes and be divided thereby between the adjacent 30 intertube spaces, the end nozzles having their longitudinal axes laterally offset from the axes of the corresponding tubes towards an intermediate nozzle, and an air supply casing surrounding said nozzles and communicating with the spaces between adjacent nozzles and said intertube spaces.

5. In combination with a furnace wall having a fuel burner port formed therein and a plurality of wall tubes uniformly spaced transversely of said port, pulverized fuel burning means arranged to discharge through the spaces between the wall tubes extending across said port and comprising a pulverized fuel conduit terminating in a series of transversely spaced fuel nozzles terminating at the outer side of the plane of said wall tubes, 45 said nozzles having elongated discharge ends arranged with their longitudinal axes parallel to the axes of and so as to have the fuel streams discharged therefrom impinge on corresponding wall tubes and be divided thereby between the adjacent intertube spaces, said nozzles being transversely spaced sufficiently to impinge only on alternate wall tubes, the end nozzles having their longitudinal axes laterally offset from the axes of the corresponding tubes towards an intermediate 55 nozzle, and an air supply casing surrounding said nozzles and communicating with the spaces between adjacent nozzles and said intertube spaces so as to provide streams of air through the intertube spaces at opposite sides of the tubes between 60 the tubes impinged upon by the fuel streams discharged from said nozzles.

RICHARD H. TILGHMAN.
